UNITED STATES PATENT OFFICE.

CHARLES R. KEERAN, OF CHICAGO, ILLINOIS.

PENCIL.

Application filed May 4, 1921. Serial No. 466,860.

To all whom it may concern:

Be it known that I, CHARLES R. KEERAN, a citizen of the United States, residing at Chicago, in the county of Cook and State 5 of Illinois, have invented certain new and useful Improvements in Pencils, of which the following is a specification.

This invention relates to a pencil having within its body means for propelling a lead 10 through one end, and having at its other end means for expelling an eraser. It is an object of this invention to produce a mechanical pencil at small cost, to operate the same with but slight effort, to renew its 15 supply of leads with no appreciable loss of time, and to render its entire structure compact and light in weight.

An exemplification of my invention is shown in the accompanying drawing in the 20 manner following:

Figure 1 is a longitudinal section through the pencil wherein is shown an active lead of nearly maximum length;

Fig. 2 is a similar view showing an active 25 lead of nearly minimum length;

Fig. 3 is an enlarged detail in longitudinal section of the parts at the head end of the pencil;

Fig. 4 is a similar view of the parts which 30 co-operate to propel the lead;

Fig. 5 is an elevation of the lead propelling plunger detached from the pencil;

Figs. 6, 7, 8 and 9 are transverse sections 35 through the pencil taken, respectively, on lines 6-6 and 7-7 of Fig. 3, 8-8 of Fig. 4, and 9-9 of Fig. 1;

Fig. 10 is a detail in transverse section taken on line 10-10 of Fig. 4;

Fig. 11 represents in elevation a plunger 40 of modified construction; and

Figs. 12 and 13 represent, respectively, a transverse section and a fragmentary elevation of a still further modification of plunger.

45 In the use that is herein made of the terms "upper" and "lower," it is to be understood that I am referring to the pencil as it is pointed in use—that is, with the eraser end up, and the writing end down.

50 The pencil body A is provided with a longitudinal bore 15 extending from end to end and slightly enlarged as at 16 for a limited distance adjacent its lower end where the walls are tapered as at 17 in the 55 form of a truncated cone. Throughout its

upper region, this bore is enlarged as at 18 to provide a magazine in which may be received a supply of reserve leads B. Extending through the axial bore of the pencil is a tube 20 that may be round, oval, rectangular, or of any other desired cross-sectional shape. Surrounding this tube near its lower end is a sleeve 21 which extends into the bore enlargement 16, being preferably formed with exterior serrations 22 (see Fig. 65 9) which frictionally engage the surrounding walls of the body to provide a non-rotatable fit therewithin. The sleeve 21 extends beyond the truncated end of the pencil, its projecting end being threaded as at 70 23 to connect with a conical tip 24 whose walls are preferably aligned with those of the truncated end 17. The tube 20 may also extend slightly beyond the sleeve 21, terminating as at 25 adjacent the end of the 75 tip 26 which is suitably formed to frictionally engage the active lead C whose end is exposed for use. Between the pencil end and tip is a plate 27 having its edges flanged to serve as a ferrule so as to protect the adjacent body material which may, if desired, be formed of wood.

The tube 20, as already stated, is preferably extended for the length of the pencil so as to penetrate the space 18 wherein are 85 accommodated the reserve leads B, the magazine thus formed being annular in shape. At its upper end the pencil body is preferably recessed as at 30 to provide a shoulder on which is rested a collar 31 which also is interiorly shouldered as at 32 to receive a plate 33 in which are formed a plurality of openings 34 communicating with the magazine. This plate is further provided with a central aperture 35 through 90 which the upper end of the tube 20 is entered, its extremity being then upset or spun out as at 36 to lock the plate, and with it the collar, upon the pencil. Through the openings 34 the reserve leads B within 100 the magazine may be removed. It is preferred that the collar should be serrated as at 37 where it engages with the body so as to be fitted non-rotatably thereupon.

The collar is further shouldered on its exterior side as at 40, the walls thereabove being threaded at 41 to receive a sleeve 42 in which is frictionally held an eraser 43 that occupies a position at the extreme upper end of the pencil. Interiorly the collar is 110

threaded as at 44 to receive a plug 45 having a head 46 which underlies the eraser to afford support thereto. By preference the threads 41 exteriorly of the collar are of greater pitch than the interior threads 44 for a purpose to be presently mentioned.

The means provided for propelling the active lead through the pencil are located within a recess 50 that is formed in one side of the body and which extends through to the tube 20 wherein is provided a registering slot 51. Arranged within the recess is a lever 52, preferably channel-shaped in cross section, and pivotally mounted upon a pin 53 which traverses the body of the pencil, as best shown in Fig. 8. This lever is pivoted at its upper end so that its end 54 which hangs downwardly may swing out from the pencil, a finger notch 55 being preferably provided to facilitate this operation. The walls of the recess 50 are suitably formed, as shown, to provide a stop 56 for the lever, so that it may normally lie flush with the body walls.

Associated with the lever is a leaf spring 60 whose lower end is secured thereto as at 61 adjacent the lower end of the lever. By reference to Fig. 10 it will be noted that the opposite walls of the lever are slotted to provide tongues 62 which may be bent around to engage with the spring to hold the same in place, the proximate end of the spring 63 being preferably turned to facilitate its retention upon the lever. The opposite end of the spring which is unsecured, is bent back upon itself and away from the lever to form a hook 65 which projects through the slot 51 into the tube 20 to engage with one of the teeth 66 of a plunger 67 such as is shown in Fig. 5. If desired, this plunger may take the form of an ordinary threaded rod 68 as shown in Fig. 11, or a square rod 69 toothed on one side, such as is shown in Figs. 12 and 13. If the latter construction be used, then it is preferred that the tube 20 should be of appropriate cross-sectional shape to co-operate with the rod to prevent its rotation therewith. The teeth or threads in the plunger extend for practically its entire length, except at its upper end where a smooth portion 70 is provided for a reason which will presently appear.

In operating the propelling mechanism of this pencil, the lower end of the lever is pulled out, whereupon the hooked end of the spring executes a circular motion which results in the toothed plunger being drawn down, the extent of such movement depending upon the extent of the arc through which the lever is swung. Upon returning the lever to its normal position, the hooked end of the spring will slide upwardly along the plunger to take up a position adjacent some tooth that lies above the one which was previously engaged. During the movement of

the lever, the hooked end of the spring which is unsecured may yield as required to permit this assumption of a new position relative to the plunger. By swinging the lever through a sufficient arc, perhaps 90 degrees as suggested in Figs. 2 and 4, the hooked end of the spring will have moved sufficiently far to disengage completely from the toothed plunger permitting the latter to be freely retracted toward the rear end of the pencil. The operation, therefore, of refilling the pencil with a new lead simply requires that this lever be swung to the position suggested, and that the pencil be turned upside down to remove the plunger, the eraser head being first removed, following which the pencil is reinverted. The plunger is thereupon reinserted to travel by gravity to the lower end of the pencil, and when all this has taken place, the lever is returned to normal position so that the hooked end of the spring will engage with one of the lower teeth of the plunger, thus preventing its movement in a rearward direction.

It will be noted that the hook at the free end of the spring is bent downwardly and obliquely toward the plunger so as to engage yieldingly with its teeth or threads to cause an intermittent propulsion of the plunger in one direction only. This constitutes in effect a ratchet mechanism whose operation is not dependent upon the character of the transverse formations in the plunger. In addition this propulsion is automatically arrested when the plunger has about reached its lowermost position in the pencil due to the fact that the smooth upper end 70 of the plunger is presented to the spring hook which then slides freely along the plunger if the lever be further oscillated. Owing to this feature of construction the parts cannot be jammed or otherwise injured when the plunger has reached the end of its travel.

The operations just described have to do with the propulsion of the lead. The eraser may also be propelled outwardly as may be required because of its wearing away in use. To accomplish this the sleeve 42 is unscrewed from the collar 31, following which the plug 45 is screwed out to a slightly higher position in the collar. The sleeve is then replaced upon the collar. As the head of the plug now occupies a somewhat higher position than formerly it will abut the eraser as the sleeve 42 is being screwed down so as to force the eraser outwardly a distance equal to that which the plug has been moved out. By forming the threads 41 relatively fast or of great pitch as compared with the threads 44 which are relatively slow or of slight pitch, I compensate for any tendency which the plug might have to revolve during the screwing movements of the sleeve 42, since if the plug should re-

volve therewith to screw back into the collar, it will move only slightly during replacement of the sleeve, thereby affecting to no appreciable extent its newly adjusted position.

It will be noted that the several parts of this pencil may be produced at very small expense and that its assembly is a very simple matter indeed. The magazine is closed by the removable eraser head so that all danger of loss of reserve leads is obviated. In addition, the pressure upon the active lead during use is transmitted back through the toothed plunger to the hooked end of the spring in a manner which tends to close the lever in place within the slot 50, thereby obviating all likelihood of the lever swinging out of the pencil during use.

I claim:

1. A pencil having in its body a longitudinal bore, a toothed plunger slidably arranged within the bore, and means for propelling the plunger comprising a lever pivoted at one end to the body, a leaf spring secured to the opposite end of the lever and extended toward its pivoted end, the free end of the spring being bent upon itself and

away from the lever to engage with the plunger whereby it may propel the same with each oscillation of the lever, substantially as described. 30

2. A pencil having a body within which is formed a longitudinal bore enlarged at the lower end of the pencil, a tube extended through the bore and secured to the upper 35 end of the pencil, a sleeve connected with and surrounding the tube near its lower end and disposed within the bore enlargement to constitute a connection between the body and tube at that end, means for non-rotatably holding the sleeve within the bore enlargement, a portion of the sleeve being extended beyond the end of the body and having threads formed thereon, a tip screwed onto the extended end of the sleeve and provided with an axial opening through which a lead may be projected, and means adapted to propel a lead longitudinally through the tube and out through the tip, substantially 40 45 as described.

CHARLES R. KEERAN.
